UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

SIDE FRAME.

Application filed September 28, 1923. Serial No. 665,446.

My invention relates to side frames for car trucks and more particularly to a wrought metal construction of side frame which is very strong and stiff but comparatively light in weight and in which maintenance charges are reduced to a minimum.

One of the principal features of the invention resides in the production of a side frame composed of a plurality of separately formed wrought metal sections each having an inner and an outer side wall portion, said sections being adapted to be abutted in horizontal planes longitudinally of the side frame and united to provide a construction of great strength value, said construction forming in effect continuous inner and outer side walls each having a plurality of top arch bar portions, bottom arch bar portions, and truck column portions.

Another object of the invention resides in the provision of a built-up side frame involving a compression member, a tension member and truck column members all of which are formed from relatively small sheet-metal blanks capable of being easily flanged, folded and united, said members being preferably connected in superimposed abutted relation.

Another object of the invention is to provide a wrought metal side frame having a tension member, a compression member, and two intermediate truck column members, the said members being connected by welding or riveting to provide a very strong and durable side frame which can be economically manufactured due to the large saving of material resulting from the formation of each of said members from a separate blank of sheet-metal.

A still further object of the invention is to provide a wrought metal side frame composed of separately formed compression member, tension member and truck columns, the compression and tension members being firmly united at their end portions by means involving a bent extension carried by one of said members and adapted to bridge the other, said bent extension being firmly connected to both of said members upon each side of their junction.

The invention further resides in the method of manufacturing car truck side frames which consists in producing a plurality of separately formed side frame members such as the compression member, tension member,

and truck column members, each of said members being produced from a sheet-metal blank shaped to provide corresponding side frame portions lying upon opposite sides of an axis of symmetry dividing the blank, flanging the marginal edges of each blank, folding said blanks, and uniting the folded blanks with their adjacent edge portions disposed in planes extending transversely of the vertical loads received by the side frame members.

There are other features of the invention pertaining to the particular relation of the parts and details of construction as will hereinafter appear.

In the drawings illustrating the invention, the scope whereof is pointed out in the claims:

Figure 1 is a view in side elevation of a wrought metal car truck side frame constructed in accordance with my invention.

Figure 2 is a vertical transverse sectional view on the line 2—2 of Figure 1.

Figure 3 is a detail horizontal cross-sectional view on the line 3—3 of Figure 1.

Figure 4 is a detail cross-sectional view on the line 4—4 of Figure 1.

Figure 5 is a detail vertical transverse sectional view on the line 5—5 of Figure 1.

Figure 6 is a detail view in side elevation of a modified form of car truck side frame in which the ends of the compression member and tension member are united by an integrally formed bridge member extending across the weld joint.

Figure 7 is a top plan view of the construction shown in Figure 6.

Referring to the drawings in which similar reference characters designate corresponding parts in the several views, my improved side frame is composed of a compression member 1, a tension member 2, and bolster or truck column members 3, said truck column members being adapted to unite the compression and tension members intermediate their ends to form the bolster opening 4. The side frame members are each formed from a sheet-metal blank having corresponding side frame portions disposed upon each side of an axis of symmetry dividing the blank.

The compression member 1 is provided with an inner sheet-metal wall 5 and an outer sheet-metal wall 6 arranged in spaced relation thereto, said side walls constitut-

ing the top arch bar portions which are preferably shaped to have the effect of a cambered compression member. Stiffening flanges 7 are provided on the lower edges 5 of the top arch bar portions, said flanges being inturned and adapted to reinforce the spaced side walls of the compression member. The lower edges of the inner and outer side walls of the compression member between the truck columns are also provided 10 with inturned stiffening flanges 8, said flanges bordering the upper portion of the bolster opening. The respective end portions of the side walls of the compression member, and more especially the lower edges 9 thereof, are adapted to be united with correspondingly formed upper edge portions 10 at the respective ends of the tension member 2.

20 The tension member 2 is formed from a sheet-metal blank having corresponding side frame portions disposed upon each side of an axis of symmetry dividing the blank. The tension member is provided 25 with an inner sheet-metal wall 11 and an outer sheet-metal wall 12, said walls constituting the bottom arch bar portions of the side frame. The upper edges of the bottom arch bar portions are provided with 30 inwardly extending stiffening flanges 13. Inwardly extending stiffening flanges 14 are provided on the beam portion of the tension member, said flanges bordering the lower portion of the bolster opening. The 35 tension member is provided with upstanding portions 15, the upper edges 16 of which are adapted to be connected to adjacent edge portions 17 of the truck columns 3.

The truck column members are each 40 formed from a sheet-metal blank having inner and outer side wall portions 18 and 19, respectively, disposed upon opposite sides of an axis of symmetry dividing the blank. Stiffening flanges 20 extend inwardly from 45 the outermost edge portions of the truck columns, said stiffening flanges providing continuations of the stiffening flanges 7 of the compression member and the stiffening flanges 13 of the tension member. The inner opposed faces of the truck columns are 50 adapted to receive bolster wear plates, said inner faces at their lower ends being offset, as at 21, and continued downwardly to overlie in vertical alinement the inwardly extending stiffening flanges 14 provided on the upstanding portions of the tension member and bordering the bolster opening. The upper ends of the truck column members, and more especially the edge portions 22 55 thereof, are adapted to be united with adjacent edge portions 23 depending from the compression member 1. The inner opposed faces of the truck column members provide continuations of the inwardly extending 60 stiffening flanges 8, the end portions of said

flanges being bent around the upper corners of the bolster opening and disposed to overlie said inner opposed faces.

The means uniting the truck columns at their respective ends to the compression and tension members involves a plurality of welds 24, said welds being designed to unite the respective abutting edge portions with the inner and outer side walls of the compression member disposed in vertical alinement with the respective inner and outer side walls of the truck columns and tension member, said respective side wall portions being united to produce in effect continuous integral sheet-metal side walls of maximum 80 strength value. The welds 24 are disposed transversely to the direction of the vertical loads received by the side frame. While I have disclosed welding means to effect the union of the truck columns with the compression and tension members, it will be understood that rivets and other connecting means may also be utilized, it being desirable, however, to maintain the side walls of the compression member in overlying 90 relation to the side walls of the tension member whereby the vertical load will be transmitted to portions best adapted to withstand the strains.

The compression and tension members are 95 united at their ends by means of a relatively long weld 25 preferably extending the full length of the abutting edges 9 and 10 of the respective members. The side wall portions of the compression member at its ends are 100 adapted to overlie the side wall portions at the ends of the tension member, the union of said side wall portions at these points providing in effect an integral continuation of the respective inner and outer side walls of 105 the side frame whereby both the vertical and longitudinal loads are effectively received by the compression and tension members.

In Figure 6 a modified construction is 110 shown wherein the end portions of the compression and tension members are also united by a bendable extension 26 provided on the compression member, said bendable extension having flanges 27 disposed against the inner opposed faces of the side wall portions 115 of the compression and tension members, said flanges being connected to the respective side walls by means of rivets 28. The flanged portions of the bendable extension are designed to bridge the weld joint between the compression and tension members 120 and provide a very rigid construction at the end of the side frame. In this construction the length of the compression member is slightly reduced to permit of the bendable extension being formed from the same blank without adding materially to the amount of metal used.

125 My improved method of manufacturing a wrought metal car truck side frame consists 130

- in forming each of the side frame members, such as the compression and tension members and truck columns, from a sheet-metal blank having corresponding side frame portions 5 which are symmetrically disposed with respect to an axis of symmetry of the blank passing between them, then bending corresponding portions of the blank to form flanges, then bending each blank along a line 10 parallel to its axis of symmetry, and finally uniting the respective blanks with their adjacent edge portions disposed transversely to the direction of the vertical loads of the side frame, the adjacent side frame portions 15 of the respective side frame members producing in effect continuous inner and outer side walls having inwardly extending stiffening flanges disposed in uninterrupted relation. 20 It will be perceived that a truck side frame embodying my invention can be economically manufactured from relatively small blanks which are capable of being easily assembled and firmly united. It will be noted that a 25 car truck side frame constructed in accordance with my invention not only has the merit of being constructed of comparatively small, light and reliable material, but its parts are so formed and combined that the 30 several side frame members can be united to withstand the greatest strains under service conditions.
- I claim:
1. A wrought metal car truck side frame having a compression member, tension member and truck column members, said members being separately formed and having their adjacent edge portions united in planes extending transversely to the direction of 35 the vertical loads imparted to the side frame.
  2. A wrought metal car truck side frame composed of a plurality of separately formed side frame members, said members having adjacent edge portions united in horizontal planes. 45
  3. A wrought sheet metal car truck side frame consisting of separately formed compression, tension and truck column members, each of said members having adjacent edge portions united by butt welding, said welding being arranged at spaced intervals longitudinally of the side frame. 50
  4. A car truck side frame comprising a tension member, a compression member and truck column members, each of said members being formed from a sheet-metal blank having adjacent edge portions united by welding, said welding being arranged at spaced intervals longitudinally of the side frame and disposed in planes extending transversely to the vertical loads imparted 55 to the side frame.
  5. A car truck side frame comprising a tension member, a compression member, and truck column members, each of said mem- 60 bers being formed from a sheet-metal blank shaped to provide inner and outer side wall portions of the frame, said members being united with adjacent edges of the inner and outer side wall portions arranged to provide continuous inner and outer side walls 65 of the side frame. 70
  6. A car truck side frame comprising a tension member, a compression member, and truck column members, each of said members being formed from a sheet-metal blank shaped to provide inner and outer side wall portions of the frame, said members being connected along adjacent edges with the inner and outer side wall portions of the 75 respective members disposed in alinement to provide continuous inner and outer side walls of the side frame. 80
  7. A car truck side frame comprising a compression member having inner and outer walls, a tension member provided with inner and outer walls, and integral truck column members each having inner and outer walls, said truck column members connecting the compression and tension members and having their inner and outer walls forming continuations of the inner and outer walls of said compression and tension members. 85
  8. A built-up car truck side frame involving a compression member having spaced inner and outer walls, a tension member formed with spaced inner and outer walls, and truck column members uniting said compression and tension members, the inner and outer walls of the compression member overlying the inner and outer walls respectively of the tension member and united therewith to form uninterrupted inner and outer surfaces. 90
  9. A built-up car truck side frame involving a compression member having inner and outer walls arranged in spaced relation, a tension member provided with inner and outer spaced walls adapted to underlie the spaced walls respectively of the compression member, and truck column members uniting said compression and tension members, said truck column members having inner and outer walls arranged in spaced relation and disposed in alinement with the 95 inner and outer walls respectively of the compression and tension members. 100
  10. A built-up car truck side frame composed of a plurality of side frame members each of which is formed with an inner sheet-metal wall integral with an outer sheet-metal wall, and means uniting said side frame members with the respective inner and outer walls of the uppermost members overlying the inner and outer walls of the lowermost 105 side frame members. 110
  11. A built-up car truck side frame composed of a plurality of side frame members each of which is formed with an inner sheet-metal wall and an outer sheet-metal wall, 115

and weld means uniting said side frame members with their respective inner and outer walls disposed in vertical alinement.

12. A built-up car truck side frame composed of a plurality of side frame members each of which is formed with an inner sheet-metal wall and an outer sheet-metal wall, and weld means uniting said side frame members in a plurality of horizontally disposed planes arranged longitudinally of the side frame.

13. A built-up car truck side frame involving a compression member, a tension member connected to said compression member, said tension member having inner and outer spaced walls, and truck column members uniting said compression and tension members, said truck column members having inner and outer walls arranged in spaced relation, the inner and outer walls of the truck column members being disposed in longitudinal alinement with portions of the inner and outer walls of the tension member.

14. A built-up car truck side frame involving a compression member, a tension member connected to said compression member, said tension member having inner and outer spaced walls, truck column members each having inner and outer walls arranged in spaced relation, and means connecting the opposite ends of the column members to the compression and tension members with the inner and outer walls of said truck column members disposed in longitudinal alinement with portions of the inner and outer walls of the tension member.

15. A wrought metal car truck side frame involving separately formed compression and tension members, truck columns uniting said members intermediate their ends, and means connecting the end portions of said compression and tension members, said means involving a longitudinal extension provided upon at least one of said members, said extension being adapted to be bent to form an end closure, overlie the joint between the compression and tension members and be connected to the other of said members.

16. A wrought metal car truck side frame involving separately formed compression and tension members with inner and outer walls, truck columns uniting said members intermediate their ends, and means connecting the end portions of said compression and tension members, said means being adapted to bridge the joint formed between the walls of the compression and tension members and being connected to each of said walls.

17. A wrought metal car truck side frame involving separately formed compression and tension members, truck columns uniting said members intermediate their ends, and means connecting the end portions of

said compression and tension members, said means including a portion of the compression member adapted to be bent to overlie the joint between the compression and tension members and be connected to said tension member.

18. A wrought metal car truck side frame involving separately formed compression and tension members, truck columns uniting said members intermediate their ends, and means connecting the end portions of said compression and tension members, said means including a bendable extension formed on the compression member, said extension being connected to the compression and tension members by riveting.

19. A built-up car truck side frame involving a compression member having inner and outer walls, a tension member having inner and outer walls underlying respectively the inner and outer walls of the compression member, means uniting the abutted edges of the respective walls of said compression and tension members, and additional means for uniting said members, said means including a member adapted to be connected to the respective walls of said members and disposed to overlie the means uniting the edge portions of said members.

20. A car truck side frame composed of separately formed compression and tension members, each of said members having inner and outer side walls, truck column members each of which is provided with inner and outer side walls, means uniting the upper ends of the truck column members to the compression member, and means uniting the lower ends of the truck column members to the tension member.

21. The method of manufacturing a wrought metal car truck side frame which consists in forming a plurality of side frame members from separate sheet-metal blanks, and uniting said members along abutted edge portions thereof disposed in planes extending transversely to vertical loads imparted to the side frame.

22. The method of manufacturing a car truck side frame which consists in producing a plurality of separately formed side frame sections such as the compression member, tension member and truck column members, each of said sections being formed from a relatively small sheet-metal blank adapted to be bent along an axis of symmetry dividing each blank into corresponding side frame portions, and uniting the bent blanks along abutted edge portions thereof.

23. The method of manufacturing a car truck side frame which consists in forming a plurality of said frame members, including bolster columns, from separate sheet-metal blanks, each of said blanks being formed with side wall portions disposed

upon opposite sides of an axis of symmetry dividing each blank, folding each blank along a line parallel to the axis of symmetry, and uniting adjacent portions of the folded blanks with the inner and outer side walls thereof respectively disposed in the same plane.

24. The method of manufacturing a car truck side frame which consists in forming the compression member, tension member and truck column members from separate sheet-metal blanks, each of said blanks being formed with correspondingly shaped side frame portions disposed upon opposite sides of an axis of symmetry dividing the blank, folding said blanks so that the side frame portions thereof produce the continuous contour of the side frame, and uniting ad-

jacent edge portions of the blank in planes disposed transversely to the vertical loads delivered to the side frame.

25. The method of manufacturing a car truck side frame which consists in forming a plurality of side frame members having corresponding side frame portions from separate sheet-metal blanks, flanging said blanks, folding each of said blanks along a line parallel to an axis of symmetry dividing said blank, and uniting the folded blanks with the corresponding inner and outer side frame portions of the members disposed in planes continuous with the contour of the side frame.

In testimony whereof I affix my signature.
